UNITED STATES PATENT OFFICE.

HUMPHREYS MILLIKEN, OF NEW YORK, N. Y., ASSIGNOR OF ONE-HALF TO JOSEPH B. TAYLOR, OF NEW YORK, N. Y.

CENTRIFUGAL DUST-SEPARATOR.

1,372,714.

Specification of Letters Patent. Patented Mar. 29, 1921.

Application filed September 20, 1919. Serial No. 325,124.

To all whom it may concern:

Be it known that I, HUMPHREYS MILLIKEN, a citizen of the United States, residing in the city and State of New York, have 5 invented a certain new and useful Improvement in Centrifugal Dust-Separators, of which the following is a specification.

My present invention has relation to a novel and improved apparatus for effecting 10 the separation of dust from air or gas by which it is held in suspension, and my improvement is especially adapted to the extraction or separation of fine dust or fumes from furnace gases and the like.

Various forms of apparatus have been 15 hitherto constructed for this general purpose, the operation of which depends upon centrifugal action set up by causing the dust-laden gases to pass through mechanism 20 to which a high rotary velocity is imparted. Apparatus of this character presents a variety of difficulties incident to practical construction and operation, among which may be mentioned the necessity of accurate balancing and specially constructed forms of 25 mounting due to the high velocities used, as well as the losses due to the inevitable clearance between the rotating and stationary parts of the apparatus.

It is a further disadvantage of the types 30 of centrifugal separators just mentioned that they require a considerable outlay of energy to drive them, besides being subject to great frictional losses and wear and tear, 35 particularly in view of the dust present in the air and gases to be treated.

It is the principal object of my present invention to provide a novel form of centrifugal dust separator having no moving 40 parts whatever; thereby avoiding all the difficulties and disadvantages above referred to.

My improved apparatus may be broadly described as comprising one or more passages for a moving current of dust laden air or gas, within which are located means for imparting a rotatory or whirling motion to the same. These passages are provided with suitable openings through which the 45 dust is driven by the centrifugal force thus created, and they are surrounded by a chamber or chambers intended to receive the dust.

In the preferred embodiment of my invention, means are further provided whereby 50 the original general movement of transla-

tion of the entering stream is gradually modified so as suitably to prepare the same for treatment within the separating apparatus. I also prefer to provide means at the outlet of my apparatus whereby the velocity 60 energy of the gases at the outlet of the separating element is converted into pressure energy tending to assist the general movement of the gases through the system.

A preferred embodiment of my invention 65 is illustrated in the accompanying drawings, wherein Figure 1 is a longitudinal sectional view of a multiple unit separator, Fig. 2 is an end elevation of the same looking from the left in Fig. 1, Fig. 3 is a view partly in 70 longitudinal section and partly in elevation of a single element or unit, Fig. 4 is a transverse section taken on the line 4—4 in Fig. 3, and Fig. 5 is an end view of a single element as seen from the right in Fig. 3. 75

In Fig. 3 is shown a single separating element on a relatively large scale, the same being interrupted in the middle to indicate indefinite length, and the portion at the left being shown partly in section and partly in 80 elevation, the central core and the helical blade being omitted for the sake of clearness.

Each separating unit comprises a tubular envelop suitably perforated and a central core carrying one or more continuous helical blades extending outwardly to the interior surface of the tubular envelop. In my preferred apparatus the dust openings take 85 the form of one or more continuous helical slits having preferably the same helical inclination as the interior helical blade or blades.

The interior of the tubular envelop is not 90 truly cylindrical but consists of successive 95 helical ridges between the slits, so arranged that the dust particles striking at any point of the interior surface will slide toward a larger radius under the action of centrifugal force, and thus be guided toward one of the 100 helical openings. These openings should be as close together as practicable, so that the dust will have to travel a minimum distance to reach any opening. Advantage is thus taken of the rolling action or eddy currents 105 of the dust-laden gas to carry the particles quickly to the nearest opening, thereby greatly enhancing the efficiency of the machine.

The preferred form of separating unit is 110

shown in Figs. 3 and 4, and comprises a tubular envelop formed by successive turns of continuous wire, 10, whose cross section—as shown in Fig. 3—presents a peak directed inwardly, so that the helical slits 11 between these wires are separated by helical ridges, as above described.

Within this envelop is located a central core 12 carrying one or more helical blades 13 extending out to the envelop and forming one or more helical passages through which the dust-laden gases are forced to travel, thus imparting to them a whirling motion.

Means are provided for uniting the spiral wires 10 to form a strong, unitary, self-supporting structure, and for this purpose I prefer to employ exterior longitudinal supporting plates 14, applied at proper intervals around the envelop, four of these being shown in Fig. 4. These plates are preferably electrically spot-welded along one edge to each of the wires crossing beneath it. In Fig. 4 the lowermost plate 14 is inclined, as shown, so as to divert the dust as it leaves the envelop toward the bottom of the casing which surrounds the separating element or elements.

This casing is shown at 15 in Figs. 1 and 2 as used with my preferred multiple-unit machine. In the form shown, the upper part of the casing is rectangular in cross section, being closed at its two ends by plates or walls 16, 17, between which extend the parallel separating elements 10. The lower portion of the casing forms a hopper 18, into which settles the dust thrown from the elements 10, which dust may be removed at intervals from the bottom 19.

During operation of the apparatus, the gas pressure within the outer closed casing is virtually equal to that within the separating elements, so that—in the ideal form—only dust will pass out through the openings 11 under centrifugal force. If the casing were open from end to end, the difference in pressures at the opposite ends of the separating elements would make itself felt in the casing. This would cause a slight flow of gases passing out of each separating element near the inlet and returning to each element near its exit, whereby a certain amount of dust would be carried back into the outgoing stream, thus reducing the efficiency of the apparatus.

In order to prevent this, the surrounding dust chamber is divided transversely into compartments by the partitions 20. These partitions surround the separating elements 10 closely, and extend far enough down at their lower edges to enter the heap of dust collecting in the bottom of the casing, which forms a seal. When the dust bin is empty, the swinging flaps 20 will hang vertically and prevent gases from passing. During

operation of the machine, these will swing inward (as shown in Fig. 1) under the weight of the dust, and permit its free passage to the exit 19.

These partitions also serve to provide means for grading the dust, it being clear that, the larger the particles separated, the sooner will they be ejected by centrifugal force, and that therefore dust of gradually increasing fineness will collect in the subdivisions placed successively farther from the inlet end of the apparatus.

The dust, as it leaves each opening in each element, will move in a nearly tangential direction, finally falling to the bottom of the dust chamber. In order to prevent the stream of dust leaving one element from interfering with that leaving an adjoining element, I prefer to employ a longitudinal dust-guiding plate 21, placed a short distance above and nearly parallel with one upper quadrant of each element, as shown in Fig. 4. This plate not only shields the element beneath it from the stream of dust leaving the element above it, but the confined space below the plate 21 promotes the formation of a rapid dust stream to one side.

It is desirable in practice to have a slight flow of gas from inside each element through the helical openings into the dust chamber at all points, in order to make sure that there is no flow of gas in the contrary direction. To accomplish this, I prefer to employ the auxiliary draft system shown in Figs. 1 and 2.

Here a blower 22 is arranged to draw gases from the main pipe 23, and to discharge the same near the bottom of the incoming gas passage 24. The main 23 is connected by branches 25 to the different dust spaces between the partitions 20, and the desired degree of draft may be adjusted for each partition by means of separate valves 26 in said branches. The essential point is that in each compartment of the dust chamber the pressure of gas should be slightly less than that just inside of the separating elements, thus insuring a slight outward flow of gas.

In order to get the best results, it is desirable that the incoming gases should assume the helical or rotating movement gradually, instead of permitting them to impinge suddenly upon the steeply pitched blades 13 while moving in a straight path.

For this purpose I employ at the inlet end of each separating element a preparing section wherein means are provided for imparting the gradually increasing rotary motion to the incoming gases. The form preferred for this means is shown in Figs. 3 and 5, as comprising one or more blades having a gradually decreasing pitch (increasing steepness) from the entrance of the preparing section onward.

I prefer to employ at least two such helical blades, 27 and 28 at the entrance of the imperforate tube 29 which forms a continuation of the tube 10. In the form shown, 5 one of the blades, as 28, is discontinued at any desired distance from the entrance (as shown, after a curve of 180 degrees) the other blade being continued, as shown at 30, with a gradually increasing steepness until 10 it merges in and is continued by the blade 13 in the separating element.

In constructing apparatus of the multiple element type, the preparing sections 29 may be located between the dust chamber wall 17 15 and a parallel wall or partition 31, through which the imperforate tubes 29 open into the intake gas passage 24.

The effect of the helical blade or blades 20 within the preparing section is to cause the various layers or elements of the entering 25 gas stream to move in parallel lines in helical paths of gradually increasing steepness, thus avoiding interfering currents and inequalities of pressure in different parts of 25 the entering stream of gases.

The efficiency of this part of my apparatus is increased by increasing the number of blades 27, 28, of gradually increasing 30 steepness, and I do not limit myself to the use of only two such blades.

In order to impart to the gases treated the necessary rotatory movement, a certain amount of energy is expended, the greater portion of which takes the form of velocity 35 energy. I have found that this can be recovered to a great extent in a form made useful in assisting the flow of gases, by providing each separating element with a helical exit funnel, as shown at the left hand 40 end of the top element in Fig. 1.

This device comprises a tube 32 within which is placed a helix or helices of the nature shown and described in connection with the preparing section, save that the 45 direction of the device is reversed and the helix now diminishes gradually in steepness toward the general exit passage 33. By the use of helices of this character, there is created a powerful forward tendency which 50 assists the progress of the gases through the apparatus.

It is to be understood that each imperforate tube 32 registers with the corresponding separating elements. As shown in Fig. 55 1, a secondary wall or partition 34 is provided for the support of the outer ends of the various tubes 32.

My invention may be embodied in a variety of modifications without departing 30 from the scope of my claims, and I do not limit myself to the details herein shown and described. What I claim is—

1. In apparatus for the centrifugal treatment of dust-laden gases, a separating element comprising a tubular envelop provided

with one or more helical slits presenting a free open passage radially and extending entirely around the periphery of the envelop, and a structure within said envelop affording a continuous helical passage in the same 70 general direction as said helical slit or slits.

2. Means of the general character set forth in claim 1 hereof, wherein the opposite edges of each slit lie mutually equidistant radially from the axis of the tubular envelop. 75

3. Means of the general character set forth in claim 1 hereof wherein the tubular envelop is provided with one or more continuous helical slits separated by sloping ridges adapted to facilitate travel of dust to said 80 slits.

4. Means of the general character set forth in claim 1 hereof, wherein the tubular envelop is composed of one or more wires helically disposed in combination with external 85 supporting plates fastened lengthwise upon the exterior of the envelop.

5. Means of the general character set forth in claim 1 hereof wherein the tubular envelop is composed of one or more wires helically disposed in combination with external 90 supporting plates spot-welded to the outside of the wire coils, and extending over the outside of said slits without entering them.

6. Means of the general character set forth in claim 1 hereof, wherein the tubular envelop is provided with external supporting plates fastened lengthwise upon the exterior of said tubular envelop, one of said plates being arranged in an inclined position to aid 100 in directing the dust as it leaves said envelop.

7. Apparatus for the centrifugal separation of dust from gas consisting of one or more separating elements of the character 105 set forth in claim 1 hereof in combination with a closed dust chamber surrounding the same.

8. Apparatus for the centrifugal separation of dust from gas consisting of one or 110 more separating elements of the character set forth in claim 1 hereof in combination with a closed dust chamber surrounding the same and one or more partitions within said chamber set transversely with respect to the 115 separating elements and fitting against the same whereby longitudinal currents within the dust chamber are prevented.

9. Apparatus for the centrifugal separation of dust from gas consisting of one or 120 more separating elements of the character set forth in claim 1 hereof in combination with a closed dust chamber surrounding the same and means whereby longitudinal currents within the dust chamber are prevented. 125

10. Apparatus for the centrifugal separation of dust from gas consisting of one or more separating elements of the character set forth in claim 1 hereof in combination with a closed dust chamber surrounding the same 130

and divided into a plurality of compartments, and means for transferring gas to the inlet ends of said elements comprising a blower, a main pipe and branch pipes with 5 valves connecting the main pipe separately with each of said compartments.

11. Dust separating apparatus comprising a plurality of separating elements of the character set forth in claim 1 hereof, a closed 10 dust chamber surrounding the same, and guide plates placed near the outer surfaces of said separating elements and adapted to prevent interference between outward dust streams from mutually adjacent elements.

12. In a centrifugal dust separator, a separating element comprising a tubular envelop having a suitable opening and a helical partition within the same in combination with a preparing section comprising a tube and two helical blades within the same whose 20 pitch decreases gradually toward the separating element; one of said blades being continuous and merging into the separating partition and the other blade extending only part way into the preparing section. 25

In testimony whereof I have hereto set my hand on this 13th day of September, 1919.

HUMPHREYS MILLIKEN.
